SEPARABLE ELECTRICAL CONNECTER

Steven Hugyik, South Bend, Ind., assignor of
one-half to Joseph Grunwald, South Bend,
Ind.

Application October 12, 1935, Serial No. 44,651

1 Claim. (Cl. 173—343)

This invention relates to a separable electrical connector, and particularly to a separable connector plug having an extension wire carried by one part thereof and a screw threaded part removably interconnected with said first part and screw threaded to fit in a threaded outlet socket.

The primary object of the invention is to provide the connector parts with novel interconnecting means in the form of an axial extension on one part and an axial receiving socket opening therefor in the other part.

A further object is to provide novel means for simultaneously spring locking and establishing electrical connection between the parts of a separable connector.

A further object is to provide a two-part article of this character with a tapered projection on one part fitting into a socket in the other part to be centered by means establishing electrical connection between the parts.

A further object is to provide an article of this character constructed to facilitate ease of application of parts, and to eliminate necessity for precision of positioning of the parts preparatory to effect an operative connection therebetween.

Other objects will be apparent from the description and the appended claim.

In the drawing:

Figure 1 is an elevational view of the device.
Figure 2 is an enlarged top plan view of one part of the device.

Figure 3 is an enlarged longitudinal sectional view of the assembled device taken on line 3—3 of Figure 2.

Figure 4 is an enlarged fragmentary longitudinal sectional view of the assembled device taken on line 4—4 of Figure 2.

Figure 5 is an enlarged fragmentary longitudinal sectional view of one part of the device taken on line 5—5 of Figure 2.

Referring to the drawing, which illustrates one embodiment of the invention in the form of a separable plug, the numeral 10 designates an electrical conductor generally in the form of an extension cord or the like and being of the usual two wire type. On the end of the cord 10 is mounted one part 11 of my improved plug, which is adapted for removable connection with a second part 12 of the plug which is adapted to be attached to a conventional screw threaded wiring outlet (not shown). Each part of the plug is formed of insulating material, such as "Bakelite". The part 11 is provided with an inner end portion 13 of relatively small diameter and an

outer or gripping portion of larger diameter. The outer end face of part 11 is recessed at 15 to provide an annular end shoulder 16, and centrally from said outer end portion axially projects an extension member 17 of generally 5 tapered or conical shape. A large diameter axial opening 18 is formed in the end 13 of part 11 and extends substantially midway of the length of the body of said part 11, and from this opening project diverging passages 19 which open in 10 the recessed end of said part in substantially diametrically opposed relation and between extension 17 and annular shoulder 16. The cord 10 is adapted to be received in the opening 18 and the individual conductors 20 and 21 there- 15 of are separated for extension of each through one of the passages 19. In substantially diametrically opposed relation, a pair of screws are secured in part 11 with the shanks thereof screw threaded in suitable longitudinal tapped open- 20 ings in said part and the heads thereof positioned in recess 15. One screw 22 is disposed adjacent the opening 19 through which conductor 20 ex- 25 tends, the bared end of said conductor being fixedly secured under the head of said screw in the conventional manner. The other screw 23 is disposed adjacent the opening 19 through which conductor 21 extends and similarly fixedly secures the bared end of that conductor. Screw 23 additionally serves to secure a contact mem- 30 ber comprising a radially extending plate 24 ap- 35 pertured to receive the shank of the screw at its outer end and positioned in face contacting en- 40 gagement with the recessed face 15 of the plug part 11. At its inner end, the plate 24 carries an integral semi-circular yoke 25 which has face 45 contacting engagement at its central portion with extension 17. From the ends of yoke 25 ex- 50 tend longitudinally directed spring arms 26 whose outer ends are provided with concavo-convex 55 heads 27. The extension 17 is preferably pro- 60 vided with a pair of opposed longitudinal flat faces 28 adjacent arms 26 and with relation to which said arms are normally outwardly spaced as best shown in Fig. 2. The tip of extension 45 17 has a button shaped conductor 29 fixed thereto, to which is fixedly electrically connected a conductor 30 extending through an L-shaped passage 31 extending longitudinally of extension 17 and thence radially in the body of part 11 50 into communication with the tapped opening receiving screw 22 whereby the shank of said screw engages, and establishes electrical connection with said conductor 30.

The plug part 12 is provided with a hand grip 55

portion 35 of a diameter preferably equal to or slightly greater than the diameter of hand grip portion 14 of part 11, and a reduced diameter portion 36 on whose outer end is fixedly secured a metal sleeve 37 configured to provide a screw thread. At its outer end sleeve 37 is preferably provided with an inwardly directed annular flange 38 in face contacting engagement with the end of plug part 12 and outwardly spaced from the center of the end of said plug part. Plug part 12 is preferably provided with a recess 39 in the face of the large diameter end thereof. An axially extending socket opening is formed in the plug part 12 in communication with recess 39. This socket opening comprises an outer portion or mouth fixedly mounting a metal ring 40 whose inner radius is preferably slightly less than the radius of yoke 25; an intermediate portion 41 of enlarged diameter; and an inner portion 42 inwardly tapered and complementary to the outer conical end of extension 17. Communicating with the inner end of portion 42 of said opening is a seat in which is fixedly mounted a metal button contact 43 whose outer end surface 44 is convex and projects beyond the threaded end of said plug part and whose inner end is preferably provided with a conical cavity 45. A longitudinally and outwardly directed passage 46 is formed in plug part 12 to extend from ring 40 to sleeve 37, and in this passage 46 is mounted a conductor 47 which is fixedly secured at its ends to said ring and sleeve. In the use of the plug, the part 12 is threaded into the conventional threaded socket of a conventional electric outlet or similar socket member whose respective terminals are engageable by the threaded sleeve 37 and button contact 43 in the manner well understood in the art. The part 11 may then be applied thereto by inserting extension 17 into the axial opening thereof. Upon the insertion of part 17, the heads 21 of contact arms 26 engage ring 40 to inwardly urge said arms until said heads pass said ring, whereupon said arms spring outwardly into engagement with ring 40 and the heads 21 thereof seat in the enlarged intermediate opening portion 41 and in engagement with the inner end or shoulder of ring 40 to spring lock said extension 17 in said opening. During the insertion of extension 17 of part 11 into part 12, the outer tapered end thereof is guided by the tapered walls of the inner opening portion 42 to properly position the parts and insure seating of both heads 21 in their receiving opening portion 41. The opening in part 12 is so proportioned with relation to part 11 and the extension thereof that when plug part 12 engages the annular wall 16 of part 11 the tapered end of extension 17 will have full contacting engagement with tapered opening portion 42 of plug part 12, the extension button contact 29 will bear against the concave face 45 of button contact 43 of plug part 12 with which it is centered, and the spring arm heads 21 will seat in socket enlargement 41. The electrical connections effected by interconnection of the plug parts are as follows: Conductor 20 of cord 10 is electrically connected through screw 22, conductor 30 and button contact 29 with button

contact 43 of plug part 12. Conductor 21 of cord 10 is electrically connected through screw 23, plate 24, yoke 25, arms 26, ring 40 and conductor 47, with threaded sleeve 37. It will also be seen that one part 12 of the plug may be rotated relative to the other, as to screw the same into a socket, thereby eliminating necessity of separating the parts or twisting the wire 10 when installing the plug.

Of primary practical importance in the construction is the fact that the spring arms 26 serve the combined functions of establishing electrical connection with ring 40, spring locking the plug parts in operative connected relation, and consequently maintaining electrical connection between button contacts 29 and 43. Another outstanding advantage of this construction is that it permits operative connection of the parts in whatever turned relation the plug parts may be from one time to another, and thus does not require same exact registration of parts, as is necessary with conventional two prong plugs. Furthermore, the extension 17 need not be initially exactly centered relative to the opening in plug part 12, but will be guided thereby upon insertion thereof in said opening, so that connection of the plug parts in poor light or in darkness is easily accomplished.

While I have illustrated my invention in the form of a separable two-part plug, it will be understood that the same may be employed in other relations, as for instance by applying the construction and arrangement of the elements of part 12 directly to an outlet member in the conventional wiring system of a building, whereby the part 12 may be directly applied to such outlet.

I claim:

A separable connector comprising a socket member, a plug member, said plug member having an axially disposed tapered extension disposed in a tapered bore in the socket member and adapted to be centered by said bore, a contact carried by the outer end of the tapered extension member, a contact carried by the socket member at its inner end and adapted to engage the extension contact, a counter-bore within the socket and surrounding the plug extension in spaced relation thereto, a conductor ring within the counter-bore surrounding the extension in spaced relation thereto, a threaded sleeve carried by the socket member and in circuit with the ring, a conductor member arching one side of the plug extension within a chamber, said conductor member having spring arms, other spring arms extending from the first mentioned spring arms at opposite sides of the plug extension and extending towards the end thereof, lugs carried by said last named arms and adapted to spring over the conductor ring when the plug sections are assembled and hold the same against axial displacement, a conductor member extending through the plug extension from the contact thereof to the chamber of the plug section, the opposite sides of the plug extension being flattened, thereby allowing a wide range of movement of the second mentioned spring arms.

STEVEN HUGYIK.
